PAGE 3

FIG. 6

FIG. 7

FIG. 8

FIG. 1 is a top plan view of a toy telephone showing my new design;

FIG. 2 is a front elevation thereof;

FIG. 3 is a side elevation thereof as viewed from the right in FIG. 2;

FIG. 4 is a rear elevation thereof;

FIG. 5 is a side elevation thereof as viewed from the right in FIG. 2 showing the cradle open and a toy figure;

FIG. 6 is a rear elevation thereof showing the cradle open;

FIG. 7 is a front elevation thereof showing the cradle open and a toy figure; and

FIG. 8 is a top plan view showing the cradle open and a toy figure.

The cord connecting the handset and base has been omitted in FIGS. 2-8 for convenience of illustration.

The present application is a continuation of my earlier co-pending application Ser. No. D. 16,106, filed Mar. 7, 1969, and entitled toy telephone.

The dominant features of my design reside in the base and grip in combination with the cradle portion, as shown.

I claim:

The ornamental design for a toy telephone, substantially as shown and described.
